United States Patent Office.

WILLIAM CUMMINGS, OF SACRAMENTO, CALIFORNIA.

Letters Patent No. 80,924, dated August 11, 1868.

IMPROVED BELT-BUCKLE.

The Schedule referred to in these Letters Patent and making part of the same.

TO ALL WHOM IT MAY CONCERN:

Be it known that I, WILLIAM CUMMINGS, of the city and county of Sacramento, California, have invented a new and improved mode of making "Belt-Buckles;" and I do hereby declare that the following is a full and exact description of the same, reference being had to the accompanying drawings, and letters of reference marked thereon.

The nature of my invention consists in having small shoulders or rings, *o*, placed near the points of the buckle, so as to prevent the belt from slipping over the points any farther than is necessary, in order to hold the belt, said points *c* being pressed through the belt and against the plate *d* in the sockets *s* by means of a back lever, *l*, to which is attached the end of the belt *b*, said lever *l* pressing down on the points *c* by means of the tension of the belt, and the pressure of the body against said lever.

What I claim as my invention, and desire to secure by Letters Patent thereon, is—

1. The points, provided with shoulders or rings near the end.
2. The lever, so arranged as to press said points through the belt and against the plate, substantially as set forth and described.

WM. CUMMINGS.
